UNITED STATES PATENT OFFICE.

JOHN J. SCHMIDT, OF WAYNESBORO, PENNSYLVANIA, AND ULRICH STEINER, OF LIMA, OHIO, ASSIGNORS TO LANDIS TOOL COMPANY, OF WAYNESBORO, PENNSYLVANIA, A CORPORATION OF PENNSYLVANIA.

CYLINDER GRINDER.

Application filed January 18, 1922. Serial No. 530,131.

Our said invention relates to an improved cylinder grinder and it is an object of the same to provide a work-holder with improved means for positioning the various cylinder blocks whose cylinders are to be ground.

A further object of the invention is to provide a machine of the character described with improved means for positioning the grinding wheel.

Another object is to provide improved bearings for the wheel spindle and still another object is to provide improved driving mechanism for the various elements of the machine.

Referring to the accompanying drawings which are made a part hereof and on which similar reference characters indicate similar parts,

Figure 1 is a front elevation of the improved machine,

Figure 2 an elevation of the same taken from the right,

Figure 3 a similar view on an enlarged scale,

Figure 4 a detail of parts shown in the preceding figures,

Figure 5 an enlarged front elevation of the work-holder,

Figure 6 an enlarged view of a cylinder gage used in connection with the work-holder,

Figure 6^a a section thereof on line 6—6 of Figure 6,

Figure 7 a face view of the workholder looking toward the right in Figure 1, part of the supporting frame being shown in section.

Figure 8 is an elevation on an enlarged scale of a reversing device shown in Figure 1,

Figure 9 a section on line 9—9 of Figure 8,

Figure 10 a vertical longitudinal section of the driving devices and bearings for the spindle of the grinding wheel,

Figure 11 a detail view of an adjustable bearing adjacent the grinding wheel, and

Figure 12 a section on line 12 of Figure 10.

In the drawings reference character 20 indicates the foundation of the machine which may be of any desirable or conventional character and may enclose within it

various elements of driving mechanism and the like as is customary in machines of this character. This frame carries groups of mechanism of which the spindle carrying and driving group is designated as a whole by reference character A, the work carrying group by reference character B and the carriage reversing devices by reference character C.

Referring first to the bearing and driving devices for the grinding spindle 21 which carries at its forward end the grinding wheel 22, these devices include a support 23 on the main or foundation frame. This support has horizontal hearings 24 and 25 in its upper portion in which is located a sleeve 26 having an eccentric bore in which is positioned a second sleeve 27 also having an eccentric bore. The sleeve 26 is mounted for rotation in its bearings, being driven by a gear 28. A housing 29 extends over said gear and is supported by bearings 24 and 25. The sleeve is held in place by an integral annular shoulder at one end and a housing 30 secured to the other end and resting against the bearing 24.

The sleeve 27 extends outward beyond the end of sleeve 26 at each end and has adjacent one end a tapered portion 31 fitting in a correspondingly tapered portion of sleeve 26. A split nut 32 has a threaded connection with the sleeve 27 and limits its movement toward the left. At the other end a tapered bushing 33 surrounds the sleeve 27 and engages an outwardly flaring portion of sleeve 26, being held in place by a bolt 34 passing through sleeve 26. A nut 36 on sleeve 27 serves to adjust the bushing 33 endwise when bolt 34 is released and a nut 35 limits the movement of the bushing. At its right-hand end the sleeve 27 is provided with a collar 38 held in place by a spline and a screw, said collar bearing teeth forming a worm wheel. A worm 39 meshes with said teeth, the ends of the worm being located in fixed bearings. In this manner means is provided for revolving the sleeve 27 in the sleeve 26 thus changing the degree of eccentricity of the spindle, the parts being so arranged that the spindle can never be quite concentric with the sleeve 26, the object being to preclude any possibility of grinding a cylinder with a wheel entirely

80

105

The bore of sleeve 27 is enlarged at both ends and contains at one end a ball-bearing for the spindle shown in detail at Figure 10. The outer casing of the ball-bearing has a groove engaged by a pin 39' carried by the extension of sleeve 27 to permit a slight endwise displacement of spindle 21. At the other end the spindle is surrounded by a sleeve 40 tapered at one end to fit within a 10 tapered opening in the sleeve 27 and having screw-threaded connection to the said sleeve. A bushing 41 is provided at one end of sleeve 40. At its other end the sleeve 40 is flared outwardly and in the flaring portion 15 is positioned a tapered split bushing 42 surrounding a reduced portion of the shaft, the slot in the bushing being wedge-shaped and having an expanding wedge 43 located therein. This wedge is adjustable longitudinally 20 of the spindle by means of a screw 44 having an eccentric pin 44' (Figure 11) projecting into a transverse slot 45 of the wedge, and the screw has threaded engagement with sleeve 40. The bushing carries at its rear 25 end a nut 46 located between a locknut 47 threaded on the bushing and a shoulder 48 thereon, the nut having threaded engagement with the interior of sleeve 40. At the left end bushing 42 bears against a shoulder 49 on shaft 21 to steady the shaft and prevent chattering. The locknut 47 projects within a guard 47' carrying the grinding wheel 22 thereby keeping dirt out of the bearing. For adjusting the outer bearing 30 of shaft 21 screw 44 is turned to withdraw the wedge 43 and permit the bushing to be moved freely endwise. Movement of the bushing to the left by turning nut 46 brings the end of the bushing against shoulder 49 and also compensates for internal wear on 35 the bushing and the nut is locked by means of the lock nut 47. When the bushing has been adjusted, screw 44 is turned to cause the wedge to again expand the bushing and so lock it in place. The pin and slot at 39' allows the spindle 21 to move in the direction of its length to a sufficient extent to permit proper adjustment of bushing 42 40 to compensate for wear between it and the 45 spindle.

The driving mechanism for the grinding wheel spindle 21 comprises a pulley 50 on a shaft 58 driven by a belt 150, the latter forming the source of power for the machine. A larger pulley 51 on the same shaft 55 drives the grinding wheel spindle through a pulley 52 and belt 53. One run of this belt passes over an idle pulley 54 and the other passes over another idler 55 mounted 60 on a swinging bracket 56 pivoted at 57 and acting as a belt tightener. The shaft 58 carrying the main pulley 51 also has fixed thereto a worm 59 (Fig. 3) driving a worm gear 60 on a shaft 61 having at the other end 65 a beveled pinion 62. This pinion in turn

drives a beveled pinion 63 on a shaft 64, which also carries a gear 65 driving a pinion 66 (Figs. 1 and 4) on a shaft 67. Shaft 67 also carries a pair of stepped pulleys 68 and 69 adapted by means of a belt 70 to 70 drive either one of a pair of stepped pulleys 71 and 72 on a shaft 73 (Figs. 1 and 10) which by means of a pinion 74 meshing with gear 28 is adapted to drive the sleeve 26. The hand wheel 75 on the same shaft serves 75 to drive the sleeve by hand when required.

The shaft carrying the pinion 66 and the pulleys 68 and 69 is mounted in a swinging bracket 76 pivoted on the shaft 64 and provided with a toggle comprising links 77, 80 78 and 79. A hand lever 80 pivoted at 81 is attached to link 79 and serves to operate the toggle to raise the bracket 76 and slacken the belt or to lower it into driving position. A fixed segment 82 has a series of holes 85 adapted to be engaged by a pin 83 in order to hold the lever in adjusted position. The pin is adapted to be retracted by a finger-operated lever 84 movable into the locking position by a spring 85. 90

The shaft 64 also carries a sprocket driving a sprocket chain 86 passing over a sprocket 87 on a shaft 88 (Fig. 9). Shafts 88, 89 and 90 are geared together and the latter shaft carries a worm 91 driving a 95 worm wheel 92 loosely journaled on a shaft 93 and pinned to sleeve 94 forming one member of a clutch. The other member 95 may be moved into and out of engagement with member 94 by means not shown. When 100 the clutch members are in engagement the shaft 93 drives the shaft 95' by means of a chain belt 96 passing over sprockets 97 and 97'. The shaft 95' carries a pinion 98' (Fig. 9) meshing with a rack 98 (Figure 7) 105 to reciprocate the work carrier in well known fashion. The reversing gearing for changing the direction of movement of the carriage may be similar to that shown in the application of Stoner No. 424,899 filed November 18, 1920, the dogging devices for controlling the same being somewhat simplified. 110

The dogging devices include a hand wheel 99 which is fixed to shaft 93 for operating the same by hand, said shaft also having 115 teeth cut into it at 100 providing a pinion to mesh with the teeth 101 on the dog wheel 102. This wheel has adjustable dogs 103 as in the above mentioned application which are adapted to strike alternately a lug 104 120 on a lever 105, the latter being provided at 106, with manual operating means. This lever is fastened to a sleeve 107 on the bearing sleeve 108 of shaft 93 and at the inner side of the frame is connected by a pin 109 125 to a sliding bar 110 adapted to be held in either one of two extreme positions by a yieldable detent 111. This bar is connected to a clutch sleeve similar to that shown at 24 in the application above referred to. 130

On the work carriage B which reciprocates longitudinally of the machine frame there is provided a work-holder 112 mounted on a transversely adjustable table 113. The work-holder is pivoted at 114 and has an adjusting screw 115 at the opposite end bearing on the transversely adjustable table. A pair of bars 116 and 117 extend across the front of the work-holder and are adapted to be adjusted up and down on the same. The cylinder block is held on these bars by means which are well known and do not require further description.

We have, however, provided novel means for determining the proper vertical position of the block. This means comprises a pair of gages 118 slidably mounted on a bar 119 extending across the face of the work-holder. This bar is supported at its ends on fixed brackets 120, being precisely positioned and held in place by conical detents 121 engaging conical openings in the bar. One of said gages is shown in detail in Figure 6 and comprises a pair of legs 122 to straddle the bar 119 and a hook-like portion 123 adapted to extend into a cylinder. Each leg of this part has a transverse opening in which is seated a movable cap 124. The caps are internally threaded and are adapted to be moved toward and from each other by a screw having opposite threads at 125 and 126 and having at an intermediate point a nut 127 integral with or fixed to the screw and having a knurled enlargement midway between its ends. A pair of set screws 128 engage flat surfaces on the caps (or longitudinal grooves therein) to prevent rotation of the caps a wheel turning device 129 is adjustably mounted on the bar 116.

In the operation of our machine a cylinder block is positioned on the workholder and fastened to the bars 116 and 117, the correct adjustment for aligning the end cylinders horizontally with the center of rotation of the sleeve 26 being determined by means of gages on bar 119. After the block is locked in place the bar 119 with the gages is removed from the workholder to permit access of the grinding wheel to the cylinders. The sleeve 27 is now adjusted to proper grinding position. It will be seen that the wheel has two movements, one of rotation on its axis and the other of revolution about the center of rotation of the sleeve 26, the sleeve 26 being driven through its gear 28 and the spindle by its pulley 32 and both moving in the same direction. The eccentric sleeve having been properly adjusted to locate the grinding wheel, this position will automatically be preserved because of the self-locking character of the adjusting means, the worm and worm wheel being substantially or entirely irreversible so that the worm wheel will not drive the worm. The

hand lever 80 is now operated to tighten the belt and thus drive the spindle, the reciprocation of the work carriage being also initiated, after which the carriage will reciprocate and the wheel will grind the cylinder as desired. 70

After grinding the cylinder the support 112 is adjusted to bring the next cylinder in line, or if preferred, the cylinder at the opposite end of the block may next be placed 75 in line with the grinding wheel after which the remaining cylinders are successively brought into grinding position. Should any of the cylinders be out of horizontal alignment as frequently happens proper alignment can be secured by manipulation of the adjusting screw 115. 80

The rotation of the wheel and the reciprocation of the work carriage may be independently arrested by means of lever 80 and manipulation of the clutch member 95. Each of them may also be independently actuated by the hand wheels shown at 75 and 99. It will be evident to those skilled in the art that many changes may be made in our 90 machine without departing from the spirit of the invention, the true scope of the invention being indicated in the appended claims. 95

Having thus fully described our said invention, what we claim as new and desire to secure by Letters Patent, is:

1. An internal grinder comprising a spindle, a grinding wheel thereon, means for imparting planetary movement to the spindle, 100 means for adjusting the orbit of the spindle, and means to prevent identification of the respective axes of rotation and of revolution of the spindle, substantially as set forth.

2. In a grinding machine a sleeve having 105 an eccentric bore, means for rotating the same, a second sleeve within the first also having an eccentric bore and having an outwardly flaring bearing at one end fitting a similar bearing on the other sleeve, a tapered 110 bushing fitting between said sleeves at the opposite end, a nut on the second sleeve for moving it longitudinally of the first to compensate for wear, said nut bearing against the outer end of said tapered bushing to 115 force it between the sleeves, a nut threaded on the bushing adjustably limiting its inward movement a spindle journaled in the inner sleeve and a grinding wheel carried by the spindle, substantially as set forth. 120

3. In a grinding machine, a sleeve, a spindle eccentrically located therein, means for varying the eccentricity of the spindle, means to rotate the spindle, and means to rotate the sleeve comprising a pulley, a shaft 125 geared thereto, a pulley on the shaft, a belt on the pulley, a driving pulley for the belt, a shaft carrying the driving pulley, a pivoted bracket in which the shaft is journaled, a driven gear on said shaft, a driving 130

- gear concentric with the pivot of the bracket and manually operated means for moving said bracket to tighten or loosen the belt without disengaging said gears, substantially as set forth.
4. In a grinding machine, a sleeve, a spindle eccentrically supported therein, means for varying the eccentricity of the spindle, means for driving the spindle and means for driving the sleeve comprising a driven pulley, gearing connecting said pulley to the sleeve, a pivoted bracket supporting a driving pulley, a belt connecting said pulleys a toggle for raising the driving pulley to render the drive inoperative, and manually actuated means for operating said toggle, substantially as set forth.
5. In a grinding machine, a sleeve, a horizontal spindle eccentrically located in the sleeve, a grinding wheel on the spindle, a main driving shaft parallel to the spindle, connections from the main shaft to drive the spindle and independent gearing driven from said shaft for driving the sleeve, substantially as set forth.
6. In a grinding machine, a rotary sleeve, a spindle carried by the sleeve and having planetary movement, a grinding wheel on the spindle, a main driving shaft below the level of the spindle, connections for driving one of said rotary members from the main driving shaft including driving and driven pulleys below and aligned with said rotary sleeve, a belt connecting said pulleys and gearing connecting the pulleys respectively to the rotary sleeve and the main shaft, connections for driving the other rotary member including a pulley on said member, a pulley on the main shaft, a belt connecting said pulleys, and a handwheel fast to the first-named driven pulley projecting between the runs of the second-named belt, substantially as set forth.
7. In a grinding machine, a rotary sleeve, a spindle carried thereby and having a planetary movement, a grinding wheel on the spindle, a main shaft below the sleeve and laterally spaced therefrom, a pulley on the spindle, a driving pulley on the main shaft, a belt connecting said driving and driven pulleys, idlers to maintain the tension of the belt, a driven pulley beneath and connected to the sleeve, a driving pulley beneath the driven pulley, a belt connecting them, connections from the main shaft to the second-named driving pulley, and means for interrupting the drive for the sleeve without stopping the spindle, substantially as set forth.
8. In a grinding machine, a sleeve, a spindle eccentrically located in the sleeve, a grinding wheel on the spindle, a main driving shaft, pulleys on said shaft and said spindle, a belt on said pulleys for driving the spindle, a pivoted bracket adjacent to the main shaft, a shaft on the bracket, a pulley on said shaft, reducing gearing connecting the main shaft to the last-named shaft, reducing gearing connected to said sleeve, said reducing gearing including a pulley, a belt connecting said pulley to the pulley on the bracket, and manual means for moving said bracket to tighten or slacken the last-named belt, substantially as set forth.
9. In a grinding machine, a sleeve, a spindle eccentrically located on the sleeve, a grinding wheel on the spindle, a main driving shaft, pulleys on said shaft and said spindle, a belt on said pulleys for driving the spindle, a pulley beneath said sleeve approximately on a level with said main shaft, connections between said pulley and the main shaft, a pulley adjacent to the sleeve, a belt connecting the last-named pulleys for driving the sleeve, and means for slackening the belt to stop the sleeve independently of the spindle, substantially as set forth.
10. A cylinder grinding machine comprising a spindle, a grinding wheel thereon, means for driving the spindle, an eccentric sleeve surrounding the spindle, a second eccentric sleeve surrounding the first, and means for driving the second sleeve said sleeves having bores so located as to prevent identification of the respective axes of rotation and revolution of the spindle, substantially as set forth.
11. An internal grinder comprising a spindle, a wheel thereon, an eccentric sleeve about the spindle, a rotary eccentric sleeve about the first-named sleeve, a bearing sleeve about the spindle between said first-named sleeve and said wheel, a bushing in the bearing sleeve, a nut threaded into the outer end of the last-named sleeve said nut abutting against a shoulder on the bushing for forcing it against a shoulder on the spindle, and a locknut on the bushing acting against the end of the first-named nut, substantially as set forth.
12. An internal grinder comprising a spindle, a wheel thereon, an eccentric sleeve about the spindle, a rotary eccentric sleeve about the first-named sleeve, a bearing sleeve about the spindle between said first-named sleeve and said wheel, a bushing in the bearing sleeve, a wedge movable lengthwise of the spindle in a wedge-shaped slot of the bushing for clamping it in place in the sleeve, and means for taking up wear between the bushing and the spindle, substantially as set forth.
13. An internal grinder comprising a spindle, a wheel thereon, an eccentric sleeve about the spindle, a rotary eccentric sleeve about the first-named sleeve, a bearing sleeve about the spindle between said first-named sleeve and said wheel, a bushing in the bearing, a wedge movable lengthwise of the spin-

dle in a wedge-shaped slot of the bushing for clamping it in place in the sleeve, and a screw projecting through the bearing sleeve said screw having an eccentric inner 5 end engaging a slot in said wedge for actuating the wedge, substantially as set forth.

14. An internal grinder comprising a spindle a wheel thereon, an eccentric sleeve about the spindle, a rotary eccentric sleeve 10 about the first-named sleeve, a bearing sleeve about the spindle between said first-named sleeve and said wheel, a tapered split bushing in a tapered recess in the bearing sleeve, means to force one end of the bushing 15 against a shoulder on the spindle whereby

the bushing contracts to compensate for wear, and a bearing engaging an opposed shoulder at the opposite end of the spindle with a limited amount of lost motion, as and for the purpose set forth. 20

In witness whereof, I have hereunto set my hand and seal at Waynesboro, Pennsylvania, this 14th day of January, A. D. nineteen hundred and twenty-two.

JOHN J. SCHMIDT. [L. S.] 25

In witness whereof, I have hereunto set my hand and seal at Lima, Ohio, this thirtieth day of December, A. D. nineteen hundred and twenty-one.

ULRICH STEINER. [L. S.]
